UNITED STATES PATENT OFFICE.

HUGH KIRKWOOD, OF MINNEAPOLIS, MINNESOTA.

DESIGN FOR A FILE-CASE FOR SALES-BOOKS.

SPECIFICATION forming part of Design No. 28,839, dated June 14, 1898.

Application filed July 3, 1897. Serial No. 643,464. Term of patent 7 years.

To all whom it may concern:

Be it known that I, HUGH KIRKWOOD, of Minneapolis, Hennepin county, Minnesota, have invented and produced a new and original Design for File-Cases for Sales-Books, of which the following is a specification, reference being had to the accompanying drawing, forming a part thereof.

The figure is a perspective view of a file-case for sales-books embodying my invention.

The invention consists in a shallow case or box C in the form of a parallelogram, as shown, and having an open top.

The leading feature of the invention consists in the novel design of the interior of the case, being subdivided longitudinally by par-

titions A, having upon either side inclined ribs B opposite correspondingly-inclined ribs D on the inner surface of the side walls of the case.

The design is completed by an inclined transverse partition F at one end of the case, forming with the end wall a triangular space E.

I claim as my invention—

The design for a file-case for sales-books, substantially as shown and described.

In testimony whereof I have hereunto set my hand this 29th day of June, A. D. 1897.

HUGH KIRKWOOD.

In presence of—

C. G. HAWLEY,
L. PAULLE.
